UNITED STATES PATENT OFFICE.

RONELLO F. PRATT, OF REVERE, AND CHARLES D. WAINWRIGHT, OF MEDFORD, MASSACHUSETTS, ASSIGNEES TO THE WAINWRIGHT MANUFACTURING COMPANY, OF PORTLAND, MAINE.

EXPANSION-JOINT.

SPECIFICATION forming part of Letters Patent No. 388,915, dated September 4, 1888.

Application filed June 22, 1887. Serial No. 242,133. (No model.)

To all whom it may concern:

Be it known that we, RONELLO F. PRATT, a citizen of the United States, residing at Revere, in the county of Suffolk and State of Massachusetts, and CHARLES D. WAINWRIGHT, a citizen of the United States, residing at Medford, in the county of Middlesex and State of Massachusetts, have invented a new and useful Improvement in Expansion-Joints, of which the following is a specification.

Our invention relates to the construction of expansion-joints used in steam or hot-water pipes or any purpose requiring an expansion-joint; and the invention consists in constructing the joint of spirally-corrugated seamless drawn tubing, the ends of which are secured in a casting provided with a flange for attachment to the line of pipes, a straight tube passing through the corrugated tube and provided at each end with a ring or stop that works freely in the casting secured to the corrugated tubing, sufficient room being allowed for the expansion and contraction of the said corrugated tubing, as more fully hereinafter described.

Referring to the accompanying drawings, Figure 1 represents a side elevation of an expansion-joint embodying our invention. Fig. 2 is an end view of the same. Fig. 3 is a cross-section taken on line xx of Fig. 1. Fig. 4 is a longitudinal section through the expansion-joint.

A represents a piece of spirally-corrugated seamless drawn tubing, the outer ends of which are inserted in a flanged ring, B, and are securely held therein by means of a ring, C, driven inside the tube A, so as to expand it and compress it between the said ring C and the flanged ring B, this being one of a number of known ways for joining a flange and tube.

We prefer to turn the ends of the tube A over at about right angles, as shown at aa , so as to insure the tube being held tight, and thereby preventing any chance of the tube working out from between the said rings.

D is a slip-tube passing through the corrugated tube and rings C C, and is provided at each end with a collar, E E, as shown, or with stops. The ring C being recessed out, as shown, so as to allow of a space for the rings E E or stops to work in, a ring, F, is screwed

into the ring C and held firmly therein by means of screws ff . (See Figs. 2 and 4.) The ring F forms a stop in one direction and a shoulder, c , forms a stop in the other direction, so that there is a clear space at each end to allow the ring C to work on the slip-tube, or the slip-tube to work in the ring C, according to the expansion or contraction of the pipes. By this arrangement of stops for the slip tube E each expansion-joint will do its proportionate part of the work—that is to say, if, for example, an expansion-joint is placed in every fifty feet in the line of pipes, then each joint will take up its proportionate part of the expansion and contraction in the entire length of pipe, thereby equalizing the amount of work done by each expansion-joint.

Each of the rings B B is provided with a flange, b , and projections or bosses $b' b'$, through which bolt-holes are formed for securing the expansion-joint in the line of pipes; or the joint may be connected by means of a screw-joint, in which case the ring F is screw-threaded on its inner side to receive the end of the pipe and the projections or bosses b' , and the bolt-holes can be dispensed with.

As steam is passed into the pipes by periodical injection, it causes the pipes to be alternately heated and cooled, causing a series of expansions and contractions to be constantly taking place in the pipes, which expansion and contraction is taken up by the spirally-corrugated tube A, thereby preserving the joints and preventing leakage.

What we claim as our invention is—

In an expansion-joint, a spirally-corrugated tube, A, connected at each end, in substantially the manner described, with a flange, B, and a slip-tube, D, provided at each end with a ring, E, in combination with the stop c upon said flange, and the stop-ring F, whereby the motion of the slip-tube is limited and the passage through the side in a straight line is uninterrupted, all as set forth.

In testimony whereof we have signed our names to this specification in the presence of two subscribing witnesses.

RONELLO F. PRATT.
CHARLES D. WAINWRIGHT.
